Primary Examiner — T Chase Nelson
Assistant Examiner — Sydney Margaret Parsley

(57) **CLAIM**

The ornamental design for a ground cover board, as shown and described.

DESCRIPTION

FIG. 1 is a front view of a ground cover board showing my new design;

FIG. 2 is a rear view of the ground cover board;

FIG. 3 is a right side view of the ground cover board;

FIG. 4 is a left side view of the ground cover board;

FIG. 5 is a top view of the ground cover board;

FIG. 6 is a bottom view of the ground cover board;

FIG. 7 is a top front side perspective view of the ground cover board; and,

FIG. 8 is a bottom rear side view of the ground cover board.

1 Claim, 6 Drawing Sheets
